UNITED STATES PATENT OFFICE.

EARL W. BEATTY, OF FALLS CITY, NEBRASKA.

COTTER PIN.

Application filed June 28, 1926. Serial No. 119,189.

The invention relates to improvements in cotter pins of the general type provided with two arms connected at one end by an eye and adapted for passage through an opening in a bolt or the like, said arms being malleable so that their free ends may be laterally bent to hold the pin against withdrawal.

Ordinarily, when using cotter pins of the type about referred to, difficulty is encountered in spreading and bending their free ends, on account of the fact that the said ends contact tightly with each other and an instrument cannot readily be inserted between them, to effect the bending operation.

It is the object of my invention to provide a new and improved cotter pin construction, in which at least one of the arms is provided with means to engage the wall of the pin receiving opening when the pin is inserted, said means serving to spread the free ends of the arms apart, so that they are readily accessible for bending.

With the foregoing in view, the invention resides in the novel subject matter hereinabove described and claimed, the description being supplemented by the accompanying drawing.

Figure 1 is an end elevation of a nut and bolt, illustrating the improved cotter pin partially inserted.

Figure 2 is a transverse section through the pin as indicated by line 2-2 of Figure 1.

Figure 3 is an elevation of the bolt and nut, partly broken away and in section, showing the pin fully inserted and disclosing the manner in which its free ends are then separated.

Figure 4 is an end elevation of the bolt and nut, showing the cotter pin secured in place by bending its ends.

Figure 5 is a side elevation of the nut, bolt and cotter pin in the relation shown in Figure 1.

The preferred form of construction is illustrated in the accompanying drawing and this construction will be herein specifically described, with the understanding that within the scope of the invention as claimed, variations may be made.

In constructing the pin, I make use of a single length of wire. This wire is bent substantially upon itself at its center, to provide an eye 6 and two arms 7 and 8 projecting from said eye, these arms being adapted for insertion through any of the well known openings adapted for cotter pin reception. As shown in Figure 2, both arms 7 and 8 are of semi-circular cross section and are provided with flat inner sides 9 which contact slidably with each other. Near the eye 6, the arm 8 is provided with a laterally bowed portion 10 which is adapted to engage the wall of the pin receiving opening, when the cotter pin is forced through said opening, said portion 10 then serving to laterally slide the arms 7 and 8 upon each other, so as to spread their free ends apart, as shown in Figure 3. Thus, these ends are readily engageable by a pair of pliers or any other desired tool, for the purpose of laterally bending them in the usual way, as shown in Figure 4, preventing accidental movement of the pin from the opening.

It will be seen from the foregoing that while the invention is exceptionally simple and inexpensive and may therefore be manufactured and marketed at small cost, it will be exceptionally desirable and when installed, will be equally as efficient as the cotter pins heretofore used.

I claim:

A cotter pin formed from a single length of wire bent substantially upon itself at its center to provide an eye and two arms projecting from said eye, said arms being of semi-circular cross section and having flat inner sides contacting slidably with each other, at least one of said arms having a laterally bowed portion near the eye to engage the wall of an opening through which the arms are forced to effect spreading of the arms at their free ends, said eye, said flat sides and said bowed portion being disposed in substantially the same plane.

In testimony whereof I have hereunto affixed my signature.

EARL W. BEATTY.
